Primary Examiner — S. Bryan Reinholdt, Jr.*Assistant Examiner* — James T Tyree(74) *Attorney, Agent, or Firm* — Fish & Richardson P.C.(57) **CLAIM**

The ornamental design for a measuring cup toy set, as shown and described.

DESCRIPTION

FIG. 1 is a first perspective view of our measuring cup toy set in a disassembled configuration;

FIG. 2 is a front view thereof;

FIG. 3 is a rear view thereof;

FIG. 4 is a right view thereof;

FIG. 5 is a left side view thereof;

FIG. 6 is a top side view thereof;

FIG. 7 is a bottom view thereof;

FIG. 8 is a bottom perspective view thereof; and,

FIG. 9 is a bottom perspective view of our measuring cup toy set in a stacked configuration.

The broken lines illustrate environmental features that form no part of the claimed design.
